UNITED STATES PATENT OFFICE.

KARL WILLIAM ARTHUR HOERNEGEL, OF POINT ROBERTS, WASHINGTON.

PICTURE-HANGER.

1,209,582.

Specification of Letters Patent. Patented Dec. 19, 1916.

Application filed November 18, 1915. Serial No. 61,328.

To all whom it may concern:

Be it known that I, KARL WILLIAM ARTHUR HOERNEGEL, a citizen of the United States, residing at Point Roberts, in the 5 county of Whatcom and State of Washington, have invented new and useful Improvements in Picture-Hangers of which the following is a specification.

This invention relates to hangers for pictures or the like which may be easily applied to the article for the hanging thereof.

The primary object of the invention is to provide a hanger which may be concealed in its entirety behind the picture to be hung, 15 moreover, obviating the use of cord or wire.

Another object of the invention is the provision of a hanger whereby the picture may be supported with the desired angularity, the parts of the hanger being concealed behind the picture, making the picture slightly 20 and adding to the appearance of the room in which a number of pictures are to be hung.

With these and other objects in view the 25 invention consists in certain novel features in the arrangement of parts, and in certain parts improvements, and combinations as will be hereinafter fully described and pointed out in the claim.

30 In the drawing, Figure 1 is a rear elevation of the hanger the parts being assembled and arranged on a picture. Fig. 2 is an end elevation thereof in use. Fig. 3 is a horizontal sectional view on line 3—3 in Fig. 2.

35 In the drawing 1 designates a flat plate which may be made of any suitable material and riveted or secured to the plate 1, in any other manner is an elongated vertical member 2. Adjustably correlated to the vertical 40 member 2, is a supplemental member 3, each member having an elongated slot to accommodate some suitable fastener, whereby the members may be securely held in any adjusted position. As shown the fastener consists of a bolt 4, and a nut 5. The supplemental member 3 is provided at its free end with an angular extension 6 for a purpose 45 hereinafter explained.

Hingedly mounted at opposite sides of the 50 plate 1, for horizontal swinging movement

are sectional arms 7 each arm comprising two members 8, and 9, the member 8 being hinged to the plate 1 as at 10, and the member 9 is adjustably correlated with the arm 8. Each of the members 8, and 9 have an 55 elongated slot to accommodate fasteners 11, whereby the arms may be increased or diminished in length. Each member 9 is notched to provide a bill 12 for a purpose presently to be described.

The picture to be hung and which is designated by the numeral 13, is provided at opposite sides with screw eyes 14, or the like, which are intended to receive the bills 12 of the members 9 after the hanger as a 60 whole has been positioned on a wall, this being accomplished by driving a nail or the like after which the hanger may be positioned, the plate 1 being provided with a keyhole opening 5 for that purpose. The 65 arms 7 by reason of their hinged connection with the plate 1 permits the plate to be moved toward or away from the picture, to permit the latter to be hung at different inclinations upon the wall. The picture besides being supported by the adjustable arms 7 is supported at its lower edge by the extension 6 of the supplemental member 3 which, as hereinabove mentioned is adjustably correlated to the vertical member 2.

70 From the foregoing description it will be evident that pictures of different dimensions may be hung and that the hanger in its entirety may be concealed behind the picture adding to the appearance when pendent, 75 moreover, owing to the adjustable nature of the arms 7 the picture may be given the desired angularity.

80 The arrangement of parts shown and described is the preferred embodiment of my 85 invention, but it is to be understood as covering all other variations in structure and arrangement which are within the scope of the claim.

85 What is claimed is:

90 The combination with a picture frame, of eyes secured to the opposed sides of the frame at the rear thereof, a plate provided with a key-hole slot adjacent one edge thereof, arms hingedly connected to the 95 100

plate at opposed sides thereof for swinging movement, a third arm depending from the lower edge of the plate, said arms including a relatively adjustable section, the said adjustable sections of the first mentioned arms terminating in hooks for engagement with said eyes, and the adjustable section of said

third arm terminating in a flange to engage the lower edge of the picture frame, and means for holding said adjustable sections 10 of said arms in fixed position.

In testimony whereof I affix my signature.

KARL WILLIAM ARTHUR HOERNEGEL.
